HANDLE FOR FEEDING-BOTTLE

Pietro Catelli, Como, Italy
(% Novelty-Misitano, A.G., Via Padova 217, Milan, Italy)

Filed Sept. 29, 1971, Ser. No. 184,993

Term of patent 14 years

Int. Cl. D9—99

U.S. Cl. D9—176

FIG. 6

FIG. 7

FIG. 1 is a side elevational view of a handle for feeding-bottle embodying my new design;

FIG. 2 is a bottom plan view of the FIG. 1;

FIG. 3 is a side elevational view as seen from the opposite side of the FIG. 1;

FIG. 4 is a top plan view of the FIG. 3;

FIG. 5 is an elevational view as seen from the left side of the FIG. 1;

FIG. 6 is an elevational view as seen from the right side of the FIG. 1; and

FIG. 7 is a front elevational view showing a modified form of my new design.

I claim:

The ornamental design for a handle for feeding-bottle, as shown and described.
